Primary Examiner — Cynthia Ramirez*Assistant Examiner* — Gino Colan(74) *Attorney, Agent, or Firm* — Yokoi & Co., U.S.A.; Toshiyuki Yokoi(57) **CLAIM**

The ornamental design for a valve, as shown and described.

DESCRIPTION

FIG. 1 shows a front view of a valve showing our new design; FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a top, front and left side perspective view thereof; and,

FIG. 8 shows a top, rear and right side perspective view thereof.

The portions of the design shown in broken lines in FIG. 6 are for the purpose of illustrating the environment only and form no part of the claimed design.

1 Claim, 5 Drawing Sheets(56)
